LAUNDRY DEVICE

Filed April 25, 1928

UNITED STATES PATENT OFFICE.

WILLIAM E. KERR, OF DES MOINES, IOWA.

LAUNDRY DEVICE.

Application filed April 25, 1928. Serial No. 272,740.

The object of my invention is to provide a laundry device of very simple and inexpensive construction, embodying more particularly a supporting means having 5 mounted thereon a member or element adapted to support a plurality of tubs or tub holders in such manner that the entire element may rotate on the support, and the respective tubs or tub holders may swing 10 with relation to the element.

With this and other objects in view, my invention consists in the construction, arrangement and combination of the various parts of my laundry device, whereby the objects contemplated are attained, as herein- 15 after more fully set forth, pointed out in my claims, and illustrated in the accompanying drawings, in which:

Figure 1 is a vertical, sectional view 20 through an upright of the kind embodying my invention, one of the tub holders thereon being shown in side elevation and another being partly broken away and partly shown in section.

Figure 2 is a horizontal, sectional view 25 taken on the line 2—2 of Figure 1.

Figure 3 is a horizontal, sectional view 30 taken on the line 3—3 of Figure 1; and

Figure 4 shows a side elevation of a fastening device used with my device.

In the accompanying drawings, I have used the reference numeral 10 to indicate an upright post, preferably hollow, having a base 12 adapted to be secured to a concrete 35 floor or otherwise 14 by means of bolts or the like 16.

An annular collar or sleeve 18 is journaled on the upright post 10 at a proper height for rotation.

The collar 18 has at its upper and lower 40 edges the annular flanges 20 and 22.

For convenience in assembling the post 10 is divided into upper and lower parts 10^a and 10^b. The portion 10^a has below its upper end an annular shoulder 24 and its upper end is screw-threaded to receive coacting screw threads on the interior of the portion 10^b. Thus in assembling the parts, the portion 10^b can be removed, the sleeve 18 can be slipped over the upper portion of the post part 10^a, and the post part 10^b can then be screwed into place.

A plurality of tub supporting devices or the like are pivoted to the flanges 20 and 22 55 of the sleeve 18. These tub supports may be made in different forms, but as here

shown, they consist in each instance of yokes 26 having at their inner ends bearings 28 journaled on upright bolts or shafts 30, mounted in the flanges 20 and 22. 60

Between the outer ends of the arms or yokes 26 are mounted the flanged rings 32. Supported by one of the rings is a grid or the like 34 upon which a basket or tub may be placed. Tubs 36 may be seated in the 65 other rings 32.

It will thus be seen that all three of the supports 26 may be swung around the post 10 at one time by rotating the sleeve 18 thereon and also that each of the supports 70 26 has limited pivotal movement on the sleeve 18. This allows for a great flexibility of adjustment of the tubs, baskets or other devices supported by the supports 26 and rings 32. By this arrangement, it is possible 75 to move the tubs so that one can step between them for greater convenience in doing the various things necessary for washing, bluing, wringing and so forth.

Preferably the post 10^a is hollow so that 80 hot and cold water pipes 38 and 40 may be extended upwardly therethrough to a mixing valve 42, having the control cocks 44 and 46 and the swinging discharge spout 48 adapted to swing to position over either of 85 the tubs on the supports 26.

Preferably also there is provided in connection with the device a gas supply pipe 50, entering the lower end of the post 10, and emerging therefrom, and supporting the 90 burner 52. Above the burner 52 is a suitable grid 54, supported by means of a bracket 56 on the post 10. The grid 54 is connected with a burner 52 by means of arms 58, so that the burner may be supported 95 from the bracket 56.

In the pipe 50 is a control cock 60.

The bottom members 36^a of the tubs are 100 preferably of the ordinary crow's foot type, but others may be used.

It is desirable to be able to move all the tubs around the upright for the reasons already mentioned. It is also important to be able to move the tubs independently of each other, so that they may be separated to permit the laundress to step between them, and also so that two tubs can be moved close together as illustrated for instance by dotted lines in Figure 2. When they are thus moved close together, clothes can be transferred from one tub to the adjacent one 105 with the least inconvenience. A wringer 110

can be swung to position above and between the two adjacent tubs for wringing from one tub into the other. A faucet 80 may be mounted on each tub for convenience when 5 draining water from them.

These advantages exist in the present device.

It is sometimes desirable to lock one tub to the member 18; so that for instance when 10 that tub is swung around the upright, the member 18 will be rotated for carrying all the tubs around the upright.

For thus locking the tubs to the member 18, I preferably provide each of the yokes 26 15 with eyes 70 and form holes 72 in the lower flange 22 of the member 18.

I then provide a fastening device 74 composed of a straight rod with ends 74^a bent at right angles as shown in Figure 4, so that 20 the ends 74^a may be dropped into an eye 70, and one of the holes 72 respectively, for thus locking one of the tubs to the rotatable element, and locking such tub against pivotal movement with relation to such element.

25 It will also be noted that the ends 74^a may be dropped into the two adjacent eyes 70, after two tubs have been swung together for thus locking the tubs together for the purposes mentioned.

30 Changes may be made in the details of the structure and arrangement of my improved laundry device without departing from the real spirit and purpose of my invention, and it is my intention to cover by 35 my claims, any modified forms of structure or use of mechanical equivalents, which may be reasonably included within their scope.

I claim as my invention:

1. A laundry device of the kind described, 40 comprising an upright support, a member mounted thereon for rotation on the support, a plurality of supporting elements pivotally mounted on said member to swing in a horizontal plane and having means to support tubs on their upper surfaces, where- 45 by said elements may be swung pivotally with relation to said member and the member may be rotated on the upright for moving all of the supporting elements simultaneously around the upright.

2. In a laundry device of the kind de- 50 scribed, an upright support, a member mounted thereon for rotation on the support, a plurality of supporting elements pivotally mounted on said member to swing in a horizontal plane and having means to

support tubs, whereby said elements may be swung pivotally with relation to said member and the member may be rotated on the upright for moving all of the supporting elements simultaneously around the upright, and a discharge spout pivotally mounted at the upper end of the upright movable to position for discharging above any of said supporting elements. 65

3. In a laundry device of the kind de- 70 scribed, an upright support, a member mounted thereon for rotation on the support, a plurality of supporting elements pivotally mounted on said member to swing in a horizontal plane and having means to support tubs, whereby said elements may be swung pivotally with relation to said member and the member may be rotated on the upright for moving all of the supporting elements simultaneously around the upright, and a burner supported on said upright, whereby any of the supporting elements may be moved to position above the burner. 75

4. A laundry device of the kind described, comprising an upright support, a member mounted thereon for rotation on the support, a plurality of supporting elements pivotally mounted on said member to swing in a horizontal plane and having means to support 80 tubs or the like, whereby said elements may be swung pivotally with relation to said member and the member may be rotated on the upright for moving all of the supporting elements simultaneously around the upright, and means whereby one of said elements may be detachably locked to said member against such pivotal movement. 90

5. A laundry device of the kind described, comprising an upright support, a member 95 mounted thereon for rotation on the support, a plurality of supporting elements pivotally mounted on said member to swing in a horizontal plane and having means to support tubs, whereby said elements may be swung pivotally with relation to said member and the member may be rotated on the upright for moving all of the supporting elements simultaneously around the upright, a burner projecting from said support, and means 100 whereby one of said elements may be detachably locked to said member against such pivotal movement for holding such element above the burner. 105

Des Moines, Iowa, March 28, 1928.

WILLIAM E. KERR.
